UNITED STATES PATENT OFFICE.

WILLIAM SCHARFHAUSEN, OF SPENCER, IDAHO.

STOVE-LID.

1,375,978.

Specification of Letters Patent. Patented Apr. 26, 1921.

Application filed May 12, 1920. Serial No. 380,717.

To all whom it may concern:

Be it known that I, WILLIAM SCHARFHAUSEN, a citizen of the United States, and a resident of Spencer, in the county of Fremont and State of Idaho, have invented certain new and useful Improvements in Stove-Lids, of which the following is a specification.

My invention is an improvement in stove lids, and has for its object to provide a lid of the character specified, wherein means is provided in connection with the lid for supplying steam to the fire box, above the burning fuel, in quantities such as to insure conservative and efficient combustion.

In the drawings:

Figure 1 is a section of a portion of a stove provided with the improved lid.

Fig. 2 is a vertical section of the lid.

Fig. 3 is a top plan view.

Fig. 4 is a vertical section of another embodiment of the invention.

In the embodiment of the invention shown in Figs. 1, 2 and 3, the improved lid comprises a ring 1 which is adapted to seat in a rabbet 2 in the stove hole 3 of a stove top 4, and this ring has a lift receiving recess 5 of usual construction for engagement by a lifter.

The internal opening 6 of the ring is beveled as shown, and a disk 7 having beveled edges is seated within the opening. This disk has a lift receiving recess 8, and by removing the disk, access may be had to the

casing 9 which is supported below and about

the internal opening of the ring, the said casing depending from the ring.

This casing 9 is designed to receive water to be evaporated by the heat in the fire box, to furnish moisture to the fire. The casing 40 has discharge openings 10 near the top for the steam and vapor, the said openings being arranged in an annular series.

In Fig. 4 there is shown a modified form, the ring 11 having the depending casing 12, 45 and the disk 13 similar to the ring, casing and disk of Fig. 1. The casing also has the annular series of openings, but in each of these openings there is arranged a nozzle or nipple 14.

In operation with water in the casing of either construction, the heat will evaporate the water, which will pass out through the openings 10, or the nipples 14, thus providing a means for increasing the efficiency of 55 the stove, and the conserving of fuel.

I claim:

A stove lid, consisting of a ring having its edge adapted to seat within the rabbeted opening of the stove, and having an 60 integral cup-shaped casing dependent from the same and co-axial with the ring and spaced apart outwardly from the opening through the ring, said casing having radial discharge openings adjacent to the ring, and 65 the edge of the opening of the ring being beveled from above outwardly and inwardly, and a disk having a beveled edge seated in the opening.

WILLIAM SCHARFHAUSEN.
